DESIGN FOR A DRESS ENSEMBLE

Marie Eileen Smith, New York, N. Y.

Application January 17, 1938, Serial No. 74,338

Term of patent 3½ years

To all whom it may concern:

Be it known that I, Marie Eileen Smith, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

The characteristic feature of my design resides in the combination on the ensemble disclosed, of the jacket member, which features the specific embroidery on the front and on the sleeves as shown.

I claim:

The ornamental design for a dress ensemble, substantially as shown, and described.

MARIE EILEEN SMITH.
